UNITED STATES PATENT OFFICE.

JOSEPH B. MURRAY, OF BROOKLYN, NEW YORK.

FOLDING STAND FOR PORTABLE HEATERS.

1,178,536.

Specification of Letters Patent. Patented Apr. 11, 1916.

Application filed January 20, 1916. Serial No. 73,123.

To all whom it may concern:

Be it known that I, JOSEPH B. MURRAY, a citizen of the United States, residing at Brooklyn, in the county of Kings and State 5 of New York, have invented a certain new and useful Improvement in Folding Stands for Portable Heaters, of which the following is a specification.

The invention is a folding stand for portable heaters, and consists in the construction 10 hereinafter set forth, whereby the device may be applied to a fuel receptacle, such as the can containing solidified alcohol now in common use, and when not so applied may 15 be folded into small and compact form.

The device is made practically in but two parts pivoted together, and is, therefore, of cheap and easy manufacture.

In the accompanying drawings—Figure 1 20 is a side elevation of my folding stand for portable heaters, showing the pivoted arm carrying the support for the object to be heated in upright position. Fig. 2 is a perspective view of the same, showing the 25 pivoted arm in folded position.

Similar letters of reference indicate like parts.

The device as here shown is constructed 30 to receive a cylindrical fuel receptacle A. A band of metal is bent preferably in ring-form, as shown at B, to receive said receptacle, and its end portions form parallel members of a projecting arm C, the said members being united preferably at their 35 ends at D. An arm E having rounded corners is pivoted at F between the members of arm C, and carries a support G, substantially U-shaped in cross section. The length of arm E is such that when said arm is 40 turned parallel to the members of arm C, the support G comes within the space bounded by ring B, as shown in Fig. 2. In this way, the device is folded so as to occupy but little space. In use, the arm E is turned 45 into upright position, as shown in Fig. 1, and the receptacle A is inserted in the ring

B. The object to be heated—as, for example, a curling iron, as indicated by dotted lines at H, Fig. 1—is laid in the support G, and when so placed extends over the receptacle A in proper position to be heated by the flame from the ignited fuel therein. 50

I claim:

1. A folding stand for portable heaters, comprising an inclosing band constructed to 55 receive a fuel receptacle, an arm laterally projecting from said band and formed of two parallel members, an arm pivoted between said members, and a support for the object to be heated carried by said pivoted 60 arm: the aforesaid parts being constructed and arranged so that when said pivoted arm is upwardly turned, said support is in position to receive the object to be heated by the fuel receptacle within said band, and 65 when, said fuel receptacle being removed, said pivoted arm is turned parallel to said projecting arm, said support lies in the space inclosed by said band.

2. A folding stand for portable heaters, 70 comprising an inclosing band constructed to receive a fuel receptacle and having its end portions extending straight and parallel to form members of a projecting arm, the said end portions being united, an arm pivoted 75 between said members, and a support for the object to be heated carried by said pivoted arm: the aforesaid parts being constructed and arranged so that when said pivoted arm is upwardly turned, said support is in position to receive the object to be heated by the fuel receptacle within said band, and when, said fuel receptacle being 80 removed, said pivoted arm is turned parallel to said projecting arm, said support lies in 85 the space inclosed by said band.

In testimony whereof I have affixed my signature in presence of two witnesses.

JOSEPH B. MURRAY.

Witnesses:

GERTRUDE T. PORTER,
MAY T. McGARRY.
